UNITED STATES PATENT OFFICE.

DONALD VIVIAN HOTCHKISS, OF HELENSBURGH, SCOTLAND.

CENTRIFUGAL PUMP, MORE PARTICULARLY THAT EMPLOYED IN HYDRAULIC PROPULSION.

1,404,525.

Specification of Letters Patent. Patented Jan. 24, 1922.

Application filed July 12, 1920. Serial No. 395,748.

(GRANTED UNDER THE PROVISIONS OF THE ACT OF MARCH 3, 1921, 41 STAT. L., 1313.)

To all whom it may concern:

Be it known that I, DONALD VIVIAN HOTCHKISS, of Helensburgh, Scotland, a subject of the King of Great Britain, have invented certain new and useful Improvements in and Relating to Centrifugal Pumps, More Particularly Those Employed in Hydraulic Propulsion, (for which I have filed application in England Jan. 7, 1919; Jan. 29, 1919; and July 7, 1919; Patent No. 134,428,) of which the following is a specification.

This invention relates to improvements in centrifugal pumps, more particularly to those employed in hydraulic propulsion, and has for its object the provision of means whereby a considerable hydrostatic head, greater ease of manipulation, higher duty and more certainty of operation may be obtained than with known forms of pumps.

The invention consists in the arrangement of a non-submerged, horizontally disposed, shrouded impeller of special form within a discharge chamber, said chamber being partly filled with air under pressure and partly filled with the fluid being pumped. The impeller is adapted to receive the fluid to be pumped, transmit it as streams while it is in co-active association therewith, and deliver it, under the action of centrifugal force, as a thin sheet of fluid into proximate receiving means which divide it into a plurality of tangential streams whose velocity is lowered and re-directed to a delivery chamber.

To reduce the friction between the structure and the fluid due to relative motion as much as possible, air injection may be provided.

In order that the invention may be the better understood, I will now proceed to describe the same in relation to the accompanying drawings, reference being had to the letters and figures marked thereon.

Like letters refer to like parts in the various figures, in which:

Fig. 1 illustrates in sectional elevation, one form of construction in accordance with this invention, the section being taken on the line 1—1 of Fig. 2.

Fig. 2 is a view illustrating the impeller and tangential receiving means drawn to a smaller scale than Fig. 1.

Fig. 3 is a section of Fig. 1 on the line 3—3 drawn to a smaller scale. 55

Referring to the drawings, the impeller α in Figs. 1 and 2 comprises a pan shaped member b having radially disposed blades c , a central boss d and a driving shaft e , the passages f between the blades c , c being of substantially constant area. The passages f communicate with a central feeding eye g which is supplied with the fluid to be pumped from a feeding chamber h of volute form, the chamber h being provided with a suction orifice i . The pan-shaped member b is formed with an upstanding edge or lip k which acts as a shrouding and compels the fluid emerging from the passages f to be discharged as a thin sheet over the edge k 70 when the impeller α is rotated. This thin sheet of fluid is received by a plurality of passages l formed in the receiving chamber m by a plurality of dividing partitions n which are so arranged that the surfaces o 75 thereof are substantially tangential to the periphery of the impeller α . By this means the sheet of fluid passing over the edge k of the member b of the impeller α is divided into a plurality of tangential or substantially tangential streams whose velocity head is, by reason of the expanding character of the passages l between the partitions n , converted mostly into pressure head, the streams being diverted downwards into the 85 chamber p where they unite and are delivered as a single stream from the discharge orifice q . Owing to the dome formation of the outside shell of the pump, the passages l naturally curve downwards until a vertical 90 portion is reached, and at this point, where the total area of the passages is as great as, or greater than, that of the impeller eye g the passages end.

Air is drawn into the eye g of the impeller α through a passage s formed in the vertical shaft, and rising through the water in the impeller α , reaches the dome chamber r above it. Alternatively the air supply may be forced into the impeller chamber α or the induction pipe by means of a pump or other compressing device. A pocket of air which effectively clears the chamber α^2 of rotating liquid is thus formed above the impeller α . Owing to the ejector action of the 105 water leaving the impeller α and entering

- the passages l , a certain amount of air is being driven continuously through the passages with the water, and on leaving the passages, this air, by the force of gravity, rises 5 to the surface of the water in the annular chamber t formed by the bowl t' of the impeller chamber and the inner shell casing under the passage l . Small holes u are drilled in the bowl t' forming the impeller 10 chamber, or alternatively float valves may be fitted at the highest convenient positions, and this air is forced through the holes or valves into the annular space between the impeller a and the impeller bowl casing t' .
- 15 It will be noticed that the pressure in the pressure chamber t is greater than that in any other part of the pump as it is the sum of the centrifugal head in the impeller a , and the head developed from the conversion of 20 the velocity head into pressure head, by the action of the passages l .

As the air enters the annular space around the impeller a , the water is forced out through the clearance w between the impeller a and the base of the pump. Owing 25 to the lip k on the impeller a , no air can escape into the space above the impeller a without overcoming the impeller head or pressure, therefore driving out the water, the 30 air follows through the clearance w and is returned to the chamber a^2 by the impeller a . Any excess of air sucked into the pump escapes through the discharge orifice q , or alternatively, may be drawn off through an 35 air escape pipe (not shown). The foregoing description will make clear that the air in the pump eliminates "disc-friction" and "dead-water" and acts as a lubricant to the water passing through the passages.

- 40 An automatic feeding device for supplying air in the quantity required may also be incorporated.

The output and power vary with the speed of rotation, and the pump may be 45 controlled by variation of the speed of the prime mover, as in other pumps, also control may be economically effected by variation of the head against which the pump is working, variation of the back pressure being brought about by any convenient method such as alteration of the length of head of water to be pumped, or, as in the case of ship propulsion, by varying the sectional area of the jet or jets. In practice, if the 55 jets are closed and the flow of liquid through the pump prevented, the centrifugal head in the impeller a only, is maintained, the impeller a revolves without absorbing further power than the frictional losses of the 60 bearings, and although the water seal between the impeller a and the passages l is broken, the impeller a remains primed. Further, a jet of small area, by reason of the restricted flow of liquid through the pump, 65 reduces the power required from the prime

mover, since less liquid is accelerated and there are little or no eddying losses.

Obviously although an impeller a having straight blades disposed radially has been described the said blades may be either 70 curved or otherwise disposed as may be found desirable to suit conditions of use, further the receiving passages l may be formed of independent tapered tubes adapted to receive the fluid sheet and deliver it in 75 substantially similar manner to that already described.

When the pump above described is to be used for jet propulsion the feeding chamber h is supplied with water by one or 80 more conduits of large cross section communicating with the external water.

Having now fully described my invention what I claim and desire to secure by Letters Patent is:—

85

1. In a centrifugal pump, the combination of a bowl-shaped impeller casing formed with a central inlet and an annular discharge, a pan-shaped impeller rotatably mounted within said casing so as to leave 90 an annular space therebetween, said impeller having a central inlet for the fluid to be pumped and an annular shrouding over which the fluid passes to the discharge of said casing, means for supplying air to 95 said casing to form an air-pad, and means for supplying air under the pressure of the pump to the space between said casing and said impeller.

2. In a centrifugal pump, the combination 100 of a bowl-shaped impeller casing formed with a central inlet and an annular discharge, tangential blades within said discharge, a pan-shaped impeller rotatably mounted within said casing so as to leave 105 an annular space therebetween, said impeller having a central inlet for the fluid to be pumped and an annular shrouding over which the fluid passes to the discharge of said casing, means for supplying air to 110 said casing to form an air-pad therein above said impeller, and means for supplying air under the pressure of the pump to the space between said casing and said impeller.

3. A centrifugal pump comprising, in combination, a pump casing formed with a feed chamber and an impeller chamber, a coned impeller in said impeller chamber, having an annular shrouding over which the pumped fluid is discharged as a thin 120 sheet, means for dividing said sheet of fluid into a plurality of tangential streams, and means for supplying air to said impeller chamber to reduce disc-friction.

4. A centrifugal pump comprising in com- 125 bination a pump casing formed with a feed chamber and an impeller chamber, a casing within said impeller chamber forming an annular discharge space therebetween, tan- gential blades within said space, an im- 130

5 peller rotatable within said casing having an annular shrouding over which the pumped fluid is discharged to said annular space and means for supplying air to the impeller chamber.

5. A centrifugal pump comprising, in combination, a pump casing formed with a volute feeding chamber and a superposed impeller chamber, a bowl-shaped casing with 10 in said impeller chamber having an outwardly and downwardly flared flange forming an annular discharge with the wall of said chamber, and a pan-shaped impeller rotatable within said casing, said impeller 15 having an annular upstanding edge constituting a shrouding over which the fluid raised by the impeller passes to said annular discharge.

6. A centrifugal pump comprising, in combination, a pump casing formed with a volute feeding chamber and a superposed impeller chamber, a bowl-shaped casing within said impeller chamber having an outwardly and downwardly flared flange 25 forming an annular discharge with the wall of said chamber, a pan-shaped impeller rotatable within said casing, said impeller having an annular upstanding edge constituting a shrouding over which the fluid 30 raised by the impeller passes to said annular discharge, and means for supplying air to said impeller chamber to form an air-pad therein when the pump is in operation.

7. A centrifugal pump comprising, in combination, a pump casing formed with a volute feeding chamber, a bowl-shaped casing within said impeller chamber having an outwardly and downwardly flared flange forming an annular discharge with the wall 35 of said chamber, substantially tangential blades in said discharge, and a pan-shaped impeller rotatable within said casing, said impeller having an annular upstanding edge constituting a shrouding over which the fluid 40 raised by the impeller passes to said annular discharge.

8. A centrifugal pump comprising, in combination, a pump casing formed with a volute feeding chamber and a superposed 50 impeller chamber, a bowl-shaped casing within said impeller chamber having an outwardly and downwardly flared flange forming an annular discharge with the wall of said chamber, substantially tangential 55 blades in said discharge, a pan-shaped impeller rotatable within said casing, said impeller having an annular upstanding edge constituting a shrouding over which the fluid raised by the impeller passes to said annu-

lar discharge, and means for supplying air 60 to said impeller chamber to form an air-pad when the pump is in operation.

9. A centrifugal pump comprising, in combination, a pump casing formed with a volute feeding chamber and a superposed 65 impeller chamber, a bowl-shaped impeller casing within said chamber and having an outwardly and downwardly flared flange forming an annular discharge with the wall of said chamber, an impeller rotatably 70 mounted within said impeller casing so as to leave an annular space therebetween, said impeller having an annular shrouding over which the pumped fluid passes to said annular discharge, means for supplying air to 75 said impeller chamber to form an air-pad therein when the pump is in operation, and means for supplying air under pressure of the pump to the space between said impeller casing and said impeller. 80

10. A centrifugal pump comprising, in combination, a pump casing formed with a volute feeding chamber and a superposed impeller chamber, a bowl-shaped impeller casing within said chamber and having an 85 outwardly and downwardly flared flange forming an annular discharge with the wall of said chamber, substantially tangential blades within said discharge, an impeller rotatably mounted within said impeller casing 90 so as to leave an annular space therebetween, said impeller having an annular shrouding over which the pumped fluid passes to said annular discharge, means for supplying air to said impeller chamber to form an air- 95 pad therein when the pump is in operation, and means for supplying air under pressure of the pump to the space between said impeller casing and said impeller.

11. A centrifugal pump comprising, in 100 combination, a pump casing formed with a feed chamber and an impeller chamber, an impeller casing in said chamber forming an annular discharge space with the wall thereof, tangential blades in said space, an 105 impeller rotatable within said impeller casing so as to leave an annular space therebetween, means for supplying air to said impeller chamber above said impeller and means for supplying air under pressure of 110 the pump to the annular space between said impeller and said impeller casing.

In testimony whereof I affix my signature in presence of two witnesses.
